UNITED STATES PATENT OFFICE.

LAWSON O. READ, OF CHATTANOOGA, TENNESSEE.

REFRIGERATOR.

SPECIFICATION forming part of Letters Patent No. 542,714, dated July 16, 1895.

Application filed November 13, 1894. Serial No. 528,655. (No model.)

To all whom it may concern:

Be it known that I, LAWSON O. READ, a citizen of the United States, residing at Chattanooga, in the county of Hamilton and State of Tennessee, have invented a new and useful Refrigerator, of which the following is a specification.

This invention relates to refrigerators; and it has for its object to provide a new and useful construction of refrigerator providing simple and efficient means for the perfect circulation of the cold and warm air, allowing the cold air to pass directly from the ice-chamber into the storage-chamber in such a manner as to effectually displace the warm air and impurities, which are conducted outside of the refrigerator without coming in contact with the ice, and thereby completing an air-circulation that forces all odors from the bottom of the refrigerator out through the top thereof, in order that the provisions may always be kept perfectly fresh and odorless.

With these and other objects in view, which will readily appear as the nature of the invention is better understood, the same consists in the novel construction, combination, and arrangement of parts hereinafter more fully described, illustrated, and claimed.

In the drawings, Figure 1 is a central vertical longitudinal sectional view of the refrigerator. Fig. 2 is a transverse sectional view on the line $z-z$ of Fig. 1. Fig. 3 is a horizontal sectional view of the refrigerator on the line $y-y$ of Fig. 1. Fig. 4 is a detail sectional view on the line $z-z$ of Fig. 1. Fig. 5 is an enlarged detail sectional view showing more clearly the connection of the inner metallic side flue-plates with the side seams of the partition floor-plate and the disposition of the lower edges of the side lining-plates for the opposite inner sides of the ice-chamber of the refrigerator. Fig. 6 is a detail in perspective of the metallic partition floor-plate.

Referring to the accompanying drawings, 1 designates a refrigerator-casing constructed in the usual substantially rectangular shape and provided at one side with the door-opening 2, adapted to be covered and uncovered by the hinged side door 3, and the said casing 1, including the door thereof, is provided with double side and end walls 4, that are faced or lined with suitable non-conducting material

in the usual way to provide non-conducting walls for the refrigerator-casing, and said double walls 4 confine therein an inclosed 55 dead-air space 5, that materially assists in providing perfectly non-conducting walls for the casing.

The refrigerator-casing 1 is open at the top and is provided with a shouldered cover-seat 6, that is adapted to snugly receive therein the air-circulating cover or lid 7, hinged at one edge, as at 8, to the top of the casing to cover and uncover the open top of the latter. Said air-circulating cover or lid 7 incloses 65 therein an air-circulating space 9 and is provided in its under side, near its opposite ends, with the air-circulating openings 10, which carry the air into the circulating-space 9, and in its outer side the said cover or lid 7 is provided with a top escape-opening 11, that forms 70 a vent or escape for the air that is directed into the air-circulating space 9, in a manner to be presently referred to, and at this point it is to be noted that when the cover or lid 7 75 10 is closed the air-circulating openings thereof are disposed within and at opposite ends of the shouldered cover-seat 6 for the cover or lid 7.

The interior of the casing 1 is faced at the 80 sides, ends, and bottom, with the inner metallic lining-plates 12, and arranged within the upper part of the casing 1 is the longitudinally-inclined metallic partition floor-plate 13. The metallic partition floor-plate 85 13 separates the interior of the casing into an upper ice-chamber 14 and a lower storage-chamber 15, within which latter chamber may be arranged suitable racks or shelves 16, of an ordinary construction for supporting the 90 provisions within the refrigerator. The partition-plate 13 forms the floor of the ice-chamber 14, and is of a substantially inverted-V shape, being provided with a central longitudinal ridge 17, that forms an apex at the 95 center under side of the said plate, and forms oppositely-inclined sides slanting toward the opposite sides of the casing. The said inverted-V shaped partition floor-plate 13, extends from end to end of the refrigerator-casing and is inclined toward one end to provide for a natural drain of water toward one end of the casing, but the said floor-plate is narrower than the width of the casing and is 100

provided at its opposite side edges with the vertically-disposed side seams 18, that are formed integrally with the plate 13 by doubling the metal upon itself at the side edges of said plate to form the upwardly-disposed flanges 19, projected above the side edges of the plate, and the depending flanges 20, extending below the side edges of the plate.

The upwardly-disposed flanges 19 of the plate 13 form longitudinal drain-gutters 21, at the sides of the plate 13, to carry the water toward one end of the refrigerator-casing, and the side seams 18, formed by the flanges 19 and 20, are adapted to snugly receive therein the upper edges of the inner metallic side flue-plates 22. The upper edges of the flue-plates 22 are fitted tightly in the side seams 18 of the floor-plate 13, to form a perfectly air-tight connection therewith, and thereby 20 absolutely cutting off any communication between the chambers 14 and 15, except by the way of the side cold-air flues 23, formed between the inner side flue-plates 22 and the inner opposite sides of the casing. The inner 25 side flue-plates 22 are spaced from the inner opposite sides of the refrigerator-casing and extend downward from the floor-plate 13 to a point short of the bottom of the casing 1 to leave bottom cold-air passages 24 at opposite 30 lower sides of the casing, through which the cold air passes into the bottom of the refrigerator from the side cold-air flues 23, into which the cold air passes from the ice-chamber over the opposite side edges of the floor-plate 13.

The upper ice-chamber 14, above the metallic partition floor-plate 13, is lined at its opposite sides and ends by the side and end metallic lining-plates 25 and 26, respectively, 40 and the side lining-plates 25 of the ice-chamber are provided at their lower edges with the outwardly-inclined drip-flanges 27, that serve to close in the top of the side cold-air flues 23, and slightly overhang the upwardly 45 disposed side-flanges 19 of the plate 13, to provide for not only protecting the cold-air flues 23, but also for directing the drip into the side drain-gutters 21, of the floor-plate 13. The floor-plate 13 is designed to support 50 thereon, within the ice-chamber 14, an ordinary slatted ice shelf or rack 28, on which is placed the ice, and at the lower ends of the longitudinal drain-gutters 21 the said plate is provided with the bottom drain-openings 55 29, in which are fitted the upper ends of the water-drain pipes 30, that extend downward through the bottom of the refrigerator casing and discharge into opposite ends of a removable water-trap pan 31.

60 The water-trap pan 31 is provided at its upper opposite edges with the side flanges 32, that removably engage a supporting-cleat 33, fixed on the bottom of the refrigerator-casing, and the turnbuckle 34, that provides for the 65 convenient removal of the water-pan when desired, and the said pan is provided with a central overflow-pipe 35, that extends through

the bottom of the pan and a slight distance up into the same, to provide for carrying off the water from said pan before the same is 70 completely filled, and said pan also serves to collect impurities and settling.

Warm-air-escape pipes 36 are arranged at opposite ends of the refrigerator-casing outside of the end lining-plates 26 of the ice-chamber, which serve to cover the sides of said pipes adjacent to the ice-chamber. The lower ends of the warm-air escape or circulating pipes 36 open into the top of the storage-chamber 15 at the opposite ends of the floor-plate 13, and the upper ends of said pipes are disposed within and at opposite ends of the cover-seat 6, and are adapted to align and communicate with the air-circulating openings 10 of the cover or lid when the latter is 85 closed.

From the foregoing it will be understood that the cold air from the ice-chamber descends through the side flues 23 into the bottom of the refrigerator and displaces the warm 90 air that collects into the apex of the floor-plate 13, and escapes out through the pipes 36 at the ends of said apex, and finally through the hollow cover 7, in the manner already referred to, thereby completing a very desirable air- 95 circulation for refrigerators.

Changes in the form, proportion, and the minor details of construction may be resorted to without departing from the principle or sacrificing any of the advantages of this invention.

Having thus described the invention, what is claimed, and desired to be secured by Letters Patent, is—

1. In a refrigerator, the casing, a longitudinally inclined inverted V-shaped partition floor-plate arranged within the casing and having side drain gutters, and bottom drain openings formed at the lower ends of said gutters, drain pipes leading downwardly from 105 said drain openings, inner metallic side flue plates spaced from the opposite inner sides of the casing and having a seam-connection at their upper edges with the side edges of said floor plate, the lower edges of said flue 110 plates terminating short of the bottom of the casing to form inner side cold air flues communicating with the casing above and below the floor plate, warm air escape pipes arranged within opposite upper ends of the casing and 115 communicating at their lower ends with the interior of the casing at the ends of the apex of the floor plate, and the top cover provided with an interior air circulating space, a top air escape opening, and oppositely located air 120 circulating openings adapted to register with the upper ends of the warm air escape pipes, 125 substantially as set forth.

2. In a refrigerator, the casing, a longitudinally inclined inverted V-shaped partition floor-plate arranged within the casing and narrower in width than the same, said floor plate being provided at its opposite side edges with vertically disposed integral side seams 130

forming longitudinal drain gutters at the side edges of the floor plate, said side seams consisting of upwardly disposed flanges and depending flanges bent downward from the upper edges of the upwardly disposed flanges, drain pipes leading from the gutters of said floor plate, inner metallic side flue plates spaced from the opposite inner sides of the casing and fitted at their upper ends in the spaces between the flanges of said side seams of the floor plate, said flue plates terminating at their lower edges short of the bottom of the casing, the side lining plates arranged above

the floor-plate and provided at their lower edges with outwardly inclined drip flanges 15 overhanging the side edges of the floor-plate, and warm air escape pipes opening into the casing at the ends of the apex of said floor plate, substantially as set forth.

In testimony that I claim the foregoing as 25 my own I have hereto affixed my signature in the presence of two witnesses.

LAWSON O. READ.
